UNITED STATES PATENT OFFICE.

WEBSTER C. ESTES, OF NEW YORK, N. Y.

DESIGN FOR A WOODEN VIAL.

SPECIFICATION forming part of Design No. 31,234, dated July 18, 1899.

Application filed June 24, 1899. Serial No. 721,789. Term of patent 14 years.

To all whom it may concern:

Be it known that I, WEBSTER C. ESTES, a citizen of the United States, residing at New York, (Brooklyn,) in the county of Kings and State of New York, have invented and produced a new and original Design for a Wooden Vial, of which the following is a specification, reference being had to the accompanying drawings, in which—

10 Figure 1 is an elevation, Fig. 2 a plan, and Fig. 3 a vertical section, illustrating my design.

15 The wooden vial is round; and the leading or material features of my design consist in the rounded edges of the body and upper edge of the stopper and the beaded upper end to the neck.

The body of the wooden vial is round, with parallel sides *a*, and the neck is round, with parallel sides *b* and of smaller diameter than *a* 20 the body. The bottom edge *d* of the body is rounded, and the upper edge *c* is similarly rounded, and the top edge *2* of the round stopper *e* is also rounded, and the upper end of the neck is provided with a semicircular 25 bead *f*.

What I claim is—

The design for a wooden vial, substantially as shown and described.

Signed by me this 20th day of June, 1899. 30
WEBSTER C. ESTES.
